UNITED STATES PATENT OFFICE.

GEORGE P. ROSE, OF FENTON, MICHIGAN.

WHIP-SOCKET.

SPECIFICATION forming part of Letters Patent No. 411,904, dated October 1, 1889.

Application filed March 22, 1888. Serial No. 268,164. (No model.)

To all whom it may concern:

Be it known that I, GEORGE P. ROSE, of Fenton, Genesee county, State of Michigan, have invented a new and useful Whip-Socket, of which the following is a specification.

This invention relates to that class of whip-sockets which have curved fronts and a central bearing.

The object of the invention is to construct a whip-socket having a longitudinally-curved front provided with lugs for attaching it to the vehicle or whatever implement or device it is attached to and a cross-piece or plate at the back, thus forming an upper and lower bearing in the front for the whip-stock to rest against and a third central bearing at the back.

This whip-socket is more especially adapted for use on road-carts, farm-wagons, agricultural implements, and such other devices and machines as require a very simple and cheap yet effectual whip-socket.

In the drawings forming part of this specification, Figure 1 is a front elevation; Fig. 2, a side elevation of the socket with a vehicle-dash in vertical section; Fig. 3, a rear elevation; and Fig. 4 is a perspective of lettered details in Fig. 3.

Referring to the lettered parts of the drawings, A is the longitudinally-curved front piece of the socket, provided with lugs e for attaching it to the dash D or to any other part of whatever implement or device to which it is desired to attach it. The back plate B is preferably made separate from the front piece and is attached thereto by suitable

means transversely at the back and vertically central, or nearly so, to form a rear bearing for the whip-stock, Fig. 2, said whip-stock having a bearing against the front piece A at the upper and lower end thereof.

As here shown, the back plate B is provided with a hole in each end, and said holes receive the pins i i on the front piece near the lugs e e, Figs. 3 and 4. These pins are clinched with a clinching-hammer, so as to hold the back plate in place across the space in the front piece occupied by the whip-stock.

Screws or any other suitable means may be employed for attaching the separable back plate to the front piece, or they may be integral.

Having thus described the invention, what I claim as new, and desire to secure by Letters Patent, is—

1. A whip-socket comprising a curved front plate having side lugs for attachment and a cross-bar extending across the rear portion of said front plate and connected to said front plate at about the center or fulcrum-point, substantially as described.

2. A whip-socket comprising a curved front plate having side lugs for attachment and a cross-bar extending across the rear portion of said front plate and connected thereto at about the center or fulcrum-point by rivets cast on the front plate and headed over the cross-bar, substantially as described.

GEORGE P. ROSE.
